UNITED STATES PATENT OFFICE.

CHARLES H. LANDENBERGER, OF PHILADELPHIA, PENNSYLVANIA.

DESIGN FOR STRIPED FABRIC.

Specification forming part of Design No. 6,695, dated June 3, 1873; application filed May 17, 1873.

To all whom it may concern:

Be it known that I, CHARLES H. LANDENBERGER, of Philadelphia, county of Philadelphia, State of Pennsylvania, have invented a design for Striped Fabric, of which the following is a specification:

The nature of my design is clearly illustrated by the figure in the accompanying drawing.

It consists of a series of parallel stripes, A, upon a plain ground, B, the latter as well as the stripes being of any desired shade or color, and the spaces between the stripes being preferably of greater width than the stripes themselves.

Each stripe A is ornamented by a longitudinal central bar, *a*, and borders *b b*, the latter having a plain exterior and a broken inner

edge, as shown. The central bar *a* has the diamond-shaped ornaments represented, and is further ornamented by bars and dots, in a manner so clearly shown in the drawing as to need no minute description.

The fabric is especially suitable for shawls and circulars.

I claim—

The design for a striped fabric, substantially as described, and as represented in and by the accompanying drawing.

In testimony whereof I have signed my name to this specification in the presence of two subscribing witnesses.

CHARLES H. LANDENBERGER.

Witnesses:

H. DORNEMANN,

ROBERT McCONNELL.
